United States Patent Office.

LOUIS D. BARTLETT, OF FITCHBURG, MASSACHUSETTS, ASSIGNOR TO
PUTNAM MACHINE COMPANY.

Letters Patent No. 66,204, dated July 2, 1867.

IMPROVEMENT IN VALVE-GEAR FOR STEAM ENGINES.

The Schedule referred to in these Letters Patent and making part of the same.

TO ALL WHOM IT MAY CONCERN:

Be it known that I, LOUIS D. BARTLETT, of Fitchburg, in the county of Worcester, and State of Massachusetts, have invented certain improvements in operating the Valves of Steam Engines as "Cut-Offs," of which the following is a full, clear, and exact description, reference being had to the accompanying drawings, making part of this specification, in which—

Figure 1 represents the valve-stem of a steam engine, together with my improved arrangement of levers and cams for operating the same.

Figures 2, 3, and 4, details to be referred to.

Figures 5 and 6 represent a modification of my invention.

My invention relates to that class of variable cut-offs for steam engines, in which the levers which lift the stems of the valves are carried in or out by the action of the governor, so that they will be lifted more or less by the revolution of cams so as to cut off the steam at the required point.

In engines constructed in accordance with the Letters Patent of the United States granted to Charles H. Brown and Charles Burleigh, on the 15th day of January, A. D. 1856, it becomes necessary to revolve the cam-shaft at a less speed than the main shaft, in order to permit the steam to follow the piston the whole length of the stroke, should the work on the engine require it. This diminution of speed renders it necessary to construct the "valve-gear" with great nicety, any inaccuracy in its construction or deviation in the angular velocity of the cam-shaft being much more perceptible in its effect upon the working of the engine than would be the case if the speed of the cam-shaft were the same as that of the main shaft, the influence on the valves being greater in proportion as the angular velocity of the cam-shaft is less than that of the main shaft. A further objection is that when the sliding lever is carried in so that the steam will be cut off near the commencement of the stroke, the cam strikes suddenly against the lever, causing noise and wear upon the parts, which in engines of large dimensions is a serious difficulty.

My invention has for its object to overcome these objections, and enable me to revolve the cam-shaft at the same speed as the main shaft, thus rendering errors in construction less apparent, and consists in making the cams in a circular form, set eccentrically upon their shaft to operate levers, the upper corners of which act upon the sliding levers which lift the valves; and my invention also consists in the employment, in combination with the circular cams, of supplementary cams or toes which serve to bring the upper corners of the eccentric levers in contact with the sliding levers, without noise, thus reducing the wear and rendering my invention peculiarly applicable to engines of large size.

To enable others skilled in the art to understand and use my invention, I will proceed to describe the manner in which I have carried it out.

In the said drawings, A is the stem of one of the inlet valves of a steam engine, which is operated by the sliding lever B, pivoted to the arm C, which is keyed to a horizontal shaft. Another arm on this shaft is connected with the governor by means of a rod, as seen in red in fig. 1, the motion of the governor being thus transmitted through the arm C to the sliding lever B. D is a lever, one end of which is connected with the arm C, by means of a pin working in a slot, a. Within the opposite end of the lever D works a circular cam, E, set eccentrically upon the cam-shaft F, which is connected by suitable gearing with the main shaft of the engine, so that both shafts will run at the same speed, and thus as the cam E is revolved, a horizontal as well as a vertical motion will be given to the lever D, the upper corner 7 of which bears against the shoulder b of the sliding lever B, so as to raise the stem A of the valve and admit steam to the cylinder as required. In proportion, however, as the balls of the governor diverge, the lever B is carried farther inward in the direction of the red arrow, fig. 1, causing the shoulder b of the lever B to lie more or less over the upper corner 7 of the lever D, and thus, as the cam revolves, the valve will be kept open for a longer or shorter space of time, according to the position of the governor-balls, while, when the governor-balls are at their highest point, the shoulder b will be carried in to such an extent that the corner 7 of the lever D will not raise the lever B as the cam is revolved, and consequently the inlet valve will remain closed. The steam is thus cut off sooner or later in proportion as the balls of the governor are more or less distended. The exhaust valves are operated by levers and cams

similarly to the steam valves, except that they are not connected with the governor, and are consequently allowed to open and close without variation.

I will now proceed to describe the device which I employ for the purpose of bringing the upper corner 7 of the lever D into contact with the sliding lever B without noise or shock, thus reducing the wear upon the parts. G, fig. 4, is a supplementary cam or toe which is attached to the cam E, and bears upon the straight portion e, (fig. 2,) of the lever D, and this cam G serves to commence the lifting of the parts which raise the valve, without noise or shock, while it also supports the lever D, (as it slides horizontally,) at such a height that its upper corner 7 will not fall below the under surface of the sliding lever B during the time occupied by a half revolution of the cam-shaft F when the valve is closed. By this arrangement the corner 7 is prevented from striking against the lever B, and all noise and shock are consequently avoided, thus reducing the wear upon the parts and rendering my invention particularly applicable to engines of large dimensions. Where the speed of the engine is high, or where the weight and strain on the valves are great, supplementary cams or toes, as above described, are essential; but in smaller engines, or where a low speed is required, the supplementary cams or toes may be dispensed with, eccentric cams only being employed to operate the levers D, as seen in figs. 5 and 6.

The above-described method of operating the valves of steam engines enables me to revolve the cam-shaft at the same velocity as the main shaft, and thus reduce any influence on the valves occasioned by inaccuracy in the construction of the "valve-gear," or deviation in the angular velocity of the cam-shaft, a desideratum heretofore unattained in that class of cut-offs which allow the steam to follow the piston throughout the whole or any part of its stroke.

Claim.

What I claim as my invention, and desire to secure by Letters Patent, is—

Operating the valve of a steam engine by means of the lever D, actuated by the eccentric cam E, in combination with the lever B, substantially as described.

I also claim, in combination with the above, the supplementary cam or toe G, operating substantially as described for the purpose set forth.

LOUIS D. BARTLETT.
